UNITED STATES PATENT OFFICE.

JAMES M. COUGHLIN, OF WILKES-BARRE, PENNSYLVANIA.

VENTILATOR.

Application filed January 10, 1927. Serial No. 160,213.

This invention relates to a ventilator for use in connection with a window sash, one of the objects of the invention being to combine a screen with the ventilator and to provide a ventilator of such construction that the window to which it is attached can be raised and lowered without disconnecting the ventilator therefrom for the purpose of regulating the supply of fresh air admitted 10 through the ventilator.

A still further object is to provide a ventilator which can be detached readily from the window sash should it be desired to raise the sash independently of the ventilator, as 15 when the window is to be cleaned.

A still further object is to provide a ventilator adjustable to window frames of different widths.

A still further object is to provide a ventilator which can be formed readily of sheet metal, the various parts being bent to proper shape.

With the foregoing and other objects in view which will appear as the description 25 proceeds, the invention resides in the combination and arrangement of parts and in the details of construction hereinafter described and claimed, it being understood that changes in the precise embodiment of the 30 invention herein disclosed may be made within the scope of what is claimed, without departing from the spirit of the invention.

In the accompanying drawings, the preferred form of the invention has been 35 shown.

In said drawings,

Figure 1 is a front elevation of the ventilator in position, a portion of the sash and 40 window frame being shown and said ventilator being open to its extreme position.

Figure 2 is a section on line 2—2, Figure 1.

Figure 3 is a view similar to Figure 2 45 showing the ventilator collapsed and the sash closed.

Figure 4 is a section on line 4—4, Figure 3.

Figure 5 is a section on line 5—5, Figure 4.

Referring to the figures by characters of reference 1 designates a base plate of sheet metal and of any desired contour, this plate being provided, at its ends, with integral 50 upstanding walls 2. Each wall has its back

edge 3 extending preferably at right angles to the plate 1 or at any rate at such an angle to said plate that when the plate is resting on a window sill, the edge 3 will be supported close to and parallel with the sash 60 S with which the ventilator is to be used. In the drawings the window sill to which the plate 1 is to be attached has been shown at W. A curled flange or bead 4 is provided along one longitudinal edge of the 65 plate 1 between the edges 3 of the walls 2, and each of the walls 2 has its top edge 5 inclined preferably as shown and merging into a lower curved portion 6 concentric with the back or curled edge portion 4 of the 70 plate 1. A narrow retaining flange 7 is extended along the edge 5—6 of each of the walls 2 and projects inwardly therefrom so as to overhang the plate 1.

An angular wing 8 projects laterally from 75 the upstanding edge 3 of each of the walls 2 and is slidably engaged by an extension plate 9 having its upper and lower edges bent over to provide retaining flanges 10 adapted to lap the wings 8. A side flange 11 is provided along the outer side edge of each extension plate 9 and this flange may be provided with keyhole slots 12 or the like whereby the flange can be detachably secured to the side of a window frame F by 80 means of screws 13 or the like. An ear 14 can be provided at the bottom edge of each of the extension plates 9 for attachment to the sill W on which the ventilator is supported. 85

The ventilator per se is made up of foldable members one of which is in the form of a metal plate 15 extending close to the side walls 2 and having a curled longitudinal edge 16 adapted to movably interlock with 90 the curled portion 4 of the plate 1 thereby to provide a hinge connection. A similar hinge connection is provided between the other longitudinal edge of the plate 15 and a metal frame 17 constituting the other member of the ventilator, this hinge connection between the members being indicated generally at 18 and including interfitting rounded portions. Frame 17 carries a screen fabric 19 and both the frame 17 and the member 15 are adapted not only to extend close to the walls 2 but also to extend close to the path of the sash S and to the inner surfaces of the flanges 7. Leaves 20 are hingedly connected to that edge portion 95 100 105 110

of the frame 17 close to the sash S and each of these leaves has a keyhole slot 21 for receiving a screw 22 or the like carried by the bottom rail of the sash S.

5 Although a particular hinge construction has been shown and described at 18 and at 4—16, it is to be understood that any desired form of hinge can be employed at each of these points.

10 The parts are so proportioned that when the sash S is closed the members 17 and 15 will be folded as shown in Figure 3. When the sash is moved upwardly it will pull through the leaves 20 upon the member 17 which, in turn, will pull upwardly on the member 15 so that the two members will swing apart and at the same time swing about the hinge connection 4—16. When the ventilator is fully extended the upper 20 edge of the frame 17 is pressed against the upper portion of the flanges 7 and the ends of said frame rest snugly against the flanges. The lower member 15 is at the same time supported in an inclined position as shown particularly in Figure 2. Consequently air flowing under the sash S will be deflected upwardly through the screen 19 as indicated by arrows in Figure 2. By lowering the sash the flow of air through the ventilator 30 can be controlled. By disconnecting the leaves 20 from the fastening devices 22, the ventilator can be collapsed and the sash

raised fully, as when it is desired to clean the same.

What is claimed is:

The combination with a window screen and a window sash, of means exposed entirely outside of the path of the sash for controlling the flow of air under the sash when open, said means including a base plate 40 mounted on the window sill of the frame, parallel walls upstanding from the base plate, adjustable means extending laterally beyond the walls for attachment to the sides of the window frame, a plate detachably 45 and hingedly connected to the base plate and having its sides in sliding engagement with the upstanding walls, a frame hingedly connected to the hinged plate and having its sides slidably engaging the upstanding 50 walls, a screen fabric carried by the frame, and means hinged to the frame for attachment to the bottom rail of the sash, said sash being adapted to close onto the sill and to move along the outer edges of the 55 upstanding walls to open and to closed position, said plate and frame being adapted to fold and unfold during the closing and opening of the sash.

In testimony that I claim the foregoing 60 as my own, I have hereto affixed my signature.

JAMES M. COUGHLIN.
